OLIVER C. SWEET, OF ALBANY, NEW YORK.

Letters Patent No. 79,412, dated June 30, 1868; antedated June 19, 1868.

IMPROVEMENT IN MACHINE FOR DRYING TUBULAR FABRICS.

The Schedule referred to in these Letters Patent and making part of the same.

TO ALL WHOM IT MAY CONCERN:

Be it known that I, OLIVER C. SWEET, of Albany, in the county of Albany, and State of New York, have invented a new and improved Machine for Drying and Finishing Tubular Fabrics; and I do hereby declare that the following is a full, clear, and exact description thereof, which will enable others skilled in the art to make and use the same, reference being had to the accompanying drawings, forming part of this specification, in which—

Figure 1 represents a side elevation, partly in section, of my improved machine for drying tubular fabrics.

Figure 2 is a vertical cross-section of the same, the plane of section being indicated by the line $z z$, fig. 1.

Figure 3 is a plan or top view of the drying-apparatus.

Figure 4 is a plan view of the bottom of the drying-apparatus.

Similar letters of reference indicate like parts.

This invention relates to a machine for drying, stretching, brushing, heating, and calendering knitted or other tubular fabric; and consists in such an arrangement of all the parts that the said fabric is completely finished and wound upon a roller, after having passed through the machine, provision being made for retaining the meshes in straight lines, and for preventing the fabric from being twisted spirally, whereby the value of the article would be greatly diminished.

A represents a frame, made of wood or other suitable material, of sufficient strength to support the other portions of the machine. A horizontal bed, a , is arranged in the frame for holding the heating and drying-apparatus, while the brushing and pressing-apparatus is suspended from horizontal arms $b b$, which are also part of the frame A.

B is a revolving platform, arranged on the bed a .

C C are horizontal rods or bars, which are hinged to the sides of the frame A, so as to swing sideways, but not up and down. The tubular fabric is packed into baskets, after having been bleached or scoured, and the baskets are then placed upon the platform B. The fabric is then strung upon one of the arms C, care being taken that it will not be twisted during the process, so that the straight lines of the meshes will be retained.

D is an upright cylinder, made of sheet metal, or other suitable material, with hollow walls, so as to leave an annular hollow chamber, c , between the outer and inner walls.

Within the cylinder D is arranged another cylinder, E, having also double walls, which enclose an annular chamber, d . Between the cylinders D and E is left an annular chamber, e , in which a spiral channel is provided, by the arrangement of a flange or tube, which is laid spirally around the inner cylinder E, and which is as wide as the chamber e . The bottom, g , of the whole cylinder D is made of cast iron, as shown, and from its centre projects an annular flange, h , on which is a shoulder, that serves to support a sheet-metal tube, F, around the lower end of which a horizontal annular flange or platform, S, is firmly arranged.

The top, i , of the cylinder is an annular plate, which only covers the chambers c , d , and e . Two sliding plates $k k$ cover the space between the tube F and the inner wall of the cylinder E.

In the upper part of the tube F is arranged a short tube, l , which has a spiral slot, through which a pin, m , passes, which is secured to the inside of the tube F.

The covering-plate of the tube l is perforated, and in its centre is a socket, for the spreader to rest in, as will be hereinafter more fully described. The tube l can be raised or lowered, by turning it, as the pin m acts against the upper or lower edge of the spiral slot in l .

$n n$ are pipes, through which steam is conducted into the chambers c and d . o is a pipe, through which a blast of air is forced into the top of the spiral channel e . Through a passage, p , the lower ends of the channel e and tube F communicate with each other, so that the blast of air forced into the top of the channel e passes around the inner cylinder E, through the channel e , and thence through the passage p , into the tube F, and and then out through the holes in the cover of the tube l .

The air becomes thoroughly heated while passing through the channel *c*, as the steam-vessels *D* and *E* surround it, and the air thus heated heats the walls of the tube *F*.

The tubular fabric, strung upon the arm *C*, is now strung upon the tube *F*, being gradually drawn from the former to the latter, and rests upon and is supported by the flange or platform *S'*. The covers *k k* are then closed, and the fabric will be partially dried on the heated tube *F*. When sufficiently dried, the spreader *G* is arranged above the drying-apparatus.

From the braces *b b* is suspended a frame, *H*, or rather two arms, in which bearings are arranged for four horizontal rollers, *q q* and *r r*, and which arms are connected at their lower ends and strengthened by a series of braces or bars, *I I*.

The spreader *G* consists of a hollow bar, *s*, in the centre of which the upper end of a vertical screw-bar, *t*, is swivelled. The upper horizontal arms of two vertical elbow-bars *u* are fitted into the said hollow bar *s*, so as to slide therein towards or from the central screw-bar *t*.

Arms *v v*, which are hinged to the bars *u* and to nuts *w*, which encircle the screw *t*, connect and hold the bars *u*.

By turning the screw *t*, the nuts *w* are either raised or lowered, and the arms *v v* brought out of their horizontal position. The aforesaid vertical arms *u* can thus be spread more or less apart, and are held in any position by means of a jam-nut, which is arranged on the screw *t*, between the nuts *w w*. The spreader can thus be adapted to fabrics of different diameters. The bar *s* is placed between two of the braces *I*, (see fig. 2,) and is thus prevented from turning.

The cap *l*, of the tube *F*, is lowered before the spreader is inserted, and is then raised, so that the lower end of the screw *t* is fitted into the socket which is provided in the centre of the cap *l*, as is clearly shown in fig. 2.

The spreader *G*, which consists of the parts *s, t, u, v, and w*, is in position to receive the fabric, when it is held between the tube *F* and rollers *r*, as herein specified. The lower ends of the bars *u* are rounded, as shown, so as not to injure the fabric. The fabric is, after having been sufficiently dried, drawn from the tube *F*, over the spreader *G*, and is thereon expanded or flattened, so as to be well led to the calendering-rollers *q* and *r*. The current of hot air passing out through the perforated cap *l* into the spread fabric, and through the meshes of the same, carries off all the moisture in the said fabric, and the same is thus thoroughly dried.

The rollers *r r* are arranged one above the other, and above them are the rollers *q q*, which are arranged alongside of each other.

The fabric is passed over the lower roller *r*, and then over the other roller, *r*, and between the nested hollow ironing-rollers *q q*, as is clearly shown in fig. 2, and is then wound upon a roller, *y*, which is arranged in the frame *H*, so as to be easily removed, when a sufficient quantity of the fabric is wound upon it.

While on the spreader *G*, the fabric can be easily adjusted, so that the lines of the weshes will be held straight by revolving the upright tube *F*.

L L are two revolving brushes, which are arranged on both sides of the rollers *r r*, and which are hung in a flexible frame, *M*. They are pressed against the fabric in the manner shown in fig. 2, so as to brush both outside faces of the same, thereby increasing its glossy and good appearance.

The rollers *q, r, y*, and *L*, are revolved by means of gear-wheels, belts, or any other suitable mechanism.

I am aware that machines for drying and finishing tubular fabrics are already in use, but they are all arranged horizontally, and no provision is made for preventing the fabric from being twisted.

By the use of the vertical revolving tube, the fabric, when once adjusted, will almost adjust itself, so as to remain straight, as the tube turns so easily that any attempt at twisting the fabric will make the tube turn until no more strain is exerted at one side of the tube than at the other.

Having thus described my invention, what I claim as new, and desire to secure by Letters Patent, is—

1. The heating-devices, consisting of the chambers *c d*, and spiral chamber *e*, passage *p*, and tube *F*, in combination with the brushing and pressing-apparatus, substantially as herein shown and described.

2. The spreader *G*, when consisting of the parts *s, t, u, v, and w*, all made and operating substantially as herein shown and described.

3. The vertical tube *F* and adjustable cap *l*, as described, in combination with the spreader *G*, made, as set forth.

4. The arrangement of the revolving platform *B*, hinged arms *C*, annular cloth-support *S*, and tube *F*; as herein described for the purpose specified.

5. The heating-cylinders *D* and *E*, constructed and arranged as described, the spiral chambers *e*, cloth-support *S*, tube *F*, spreader *G*, heating and ironing-rollers *q* and *r*, and brushes *L*, all made and operating substantially as and for the purpose herein shown and described.

OLIVER C. SWEET.
